Specification for Design.

Patented May 28, 1918.

Application filed June 8, 1916. Serial No. 102,586. Term of patent $3\frac{1}{2}$ years.

To all whom it may concern:

Be it known that I, HELEN MATHEWSON, a citizen of the United States, residing at Los Angeles, in the county of Los Angeles and State of California, have invented a new, original, and ornamental Design for a Combined Door and Door-Grille, such combined door and door-grille being a separate article of manufacture, of which the following is a specification, reference being had to the accompanying drawing, forming a part thereof.

The figure is a perspective view of a door and grille showing my new design.

I claim:

The ornamental design for a combined door and door grille as shown.

HELEN MATHEWSON.
